UNITED STATES PATENT OFFICE.

CHARLES M. BUTTS, OF ORVILLE, CALIFORNIA.

SUBGRADE DRAG.

Application filed July 26, 1919. Serial No. 313,924

To all whom it may concern:

Be it known that I, CHARLES M. BUTTS, a citizen of the United States, residing at Orville, in the county of Butte and State of California, have invented certain new and useful Improvements in Subgrade Drags, of which the following is a specification.

This invention relates to highway or road building implements, and an object of the invention is to provide a device for building a sub-grade for paved highways, which will eliminate considerable of the manual labor ordinarily necessary in the forming of a sub-grade.

15 In the construction of concrete or analogous highways, it is necessary to build a sub-grade, or a foundation upon which the paving material is laid, this foundation or sub-grade must be uniform to insure an even 20 thickness of the concrete, asphalt or analogous highway paving substance, and in the majority of sections of the country a curved sub-grade is made substantially four inches below the finished pavement.

25 It is an object of this invention to provide a device, which will travel upon the head board or concrete form along the sides of the highway, and which will level and properly form the foundation or sub-grade, cutting off 30 the high places and filling in the low places, and also cutting or forming this foundation or sub-grade in the proper shape to form a shed for draining water to the sides of the highway, and which drag structure specifically includes a carrying frame having ferrules or cutting teeth at its forward end, for 35 loosening the soil in the high places and having positioned rearwardly thereof a plurality of cutting blades which also act as scrapers and are set, one slightly below the one 40 next in front thereof, so as to form a gradual cutting away of the down surface to form the sub-grade or foundation for the highway.

A further object of the invention is to provide suitable conveyor structures, which are provided for carrying surplus soil to the sides of the highway and for eliminating the necessity of manual shovelling of this surplus soil out of the highway bed and to 45 provide means, engageable with the upper edge of one of the forms or header boards of the road bed construction which will operate the conveyors during the travel of the grader.

In use, this grader is particularly designed 55 to be drawn over the highway by a roller, of any approved type such as are commonly employed for rolling highway surfaces, and since it is necessary to roll the foundation or subgrade after it has been properly formed 60 by the grader, it is necessary to provide means to facilitate the lateral movement of the grader to permit the roller, normally employed for propelling the drag to pass rearwardly thereof for rolling the surface recently formed by the drag, and it is an object of this invention to provide means in a drag structure as specified, whereby the drag may be moved laterally with comparative 70 ease, the said structure comprising a jack carried by the superstructure which is in turn supported by the frame of the drag and which has a track structure carried thereby upon which a pair of rollers engage, said rollers being connected to the track 75 structure, so that when the drag structure is elevated by means of the jack structure, off the headerboard, it will roll laterally or may be easily moved to one side, to permit the roller to pass rearwardly thereof, after which 80 the drag structure may be easily returned to its normal position and reversed, as to its direction in which its grading or cutting blades extend, in case it is necessary or desirable to return over the foundation or subgrade previously made thereby.

85 Other objects of the invention will appear from the following detailed description taken in connection with the accompanying drawings, forming a part of this specification, and in which drawings:

Figure 1 is a top plan of the improved sub-grade drag or grader.

Figure 2 is an end elevation of the sub-grade drag showing the same in an elevated 95 position to which it is moved by means of the jack structure.

Figure 3 is a side elevation of the drag.

Figure 4 is a longitudinal section through the drag.

Figure 5 is a fragmentary cross section through the drag illustrating the jack structure associated therewith.

Figure 6 is a fragmentary section through a part of the drag structure.

Figure 7 is a detail view illustrating a part 105 of one of the carriers employed for carrying the surplus dirt to the sides of the highway.

Figure 8 is a fragmentary top plan of the jack structure.

Figure 9 is a detail section illustrating the manner of connecting the harrow teeth to their supporting bars.

Figure 10 is a detail view of one of the jack levers, and

Figure 11 is a detail view partly in section of a part of the drag structure.

Referring more particularly to the drawings, wherein like characters indicate like and corresponding parts throughout the several views, 15 designates the main supporting frame of the drag or grader structure, 15 which comprises side rails 16 and 17 connected by suitable cross braces 18 and 19, the ends of the side rails 16 being braced by suitable angle braces 20. The cross braces 18 and 19 have levers 21 pivotally connected thereto, one at each corner of the frame 15, and these levers are held in various adjusted positions through the medium of stop bolts 22 which engage through any one of a series of openings 23 formed in standards 24 which are carried by the side rails 16 and 17 at their ends. The inner end of the levers 21 are connected through the medium of links 25 with a tool carrying frame 26 which frame is adjusted vertically by means of the 30 levers 21.

The frame 26 carries a pair of cross bars 27 and 28 at its forward end, preferably formed of channel iron and these cross bars each have a plurality of harrow teeth 29 connected thereto in any approved manner, preferably by means of U shaped bolts 30 as clearly shown in Figures 4 and 9 of the drawings, so as to permit adjustment of the position of the individual teeth with respect 40 to their carrying bar. These teeth are preferably arranged in staggered rows, that is, the teeth carried by the supporting bar 28 are preferably disposed staggeringly with respect to the teeth 29 carried by the forward cross supporting bar 27, thus effecting a thorough breaking up of any soil surface with which they engage.

A cross bar 31 is positioned rearwardly of the cross bar 28 and as shown in Figures 1 50 and 4 of the drawings it is divided intermediate the side rails 16 and 17, to accommodate the frame structure 32. The cross bar 31 has a cutting blade 32^a connected to each section thereof, which cutting blade is 55 preferably positioned at an angle of substantially 30° to the vertical, so as to provide an inclined or angled cutting surface for engagement with the soil after it has been broken up or loosened by the harrow teeth 60 29. The lower cutting edge of the blade 32^a is preferably positioned at approximately two inches above the desired finished level of the foundation or sub-grade.

Cross bars 33 and 34 are positioned rear-

wardly of the cross bar 31 and they carry 65 cutting blades 35 and 36 respectively, which are also positioned at an angle of approximately 30° to the vertical or parallel with the cutting blade 32^a, to which they are similar in construction. The cutting edge of 70 the blade 35 is preferably positioned approximately one inch below the cutting edge of the blade 32^a, and also one inch above the finished surface of the subgrade, while the cutting edge of the blade 36 is positioned at 75 substantially one inch below the cutting edge of the blade 35 or at the elevation at which the sub-grade surface is to be finished, and thus it will be seen that by the gradual increasing of the depth of the blade, rearwardly from the forward or foremost blade, the sub-surface or foundation of the highway will be gradually cut and levelled. These blades 32^a, 35 and 36 are shaped, to 80 conform to the desired shape of the foundation or sub-surface, as clearly shown in Figure 2 of the drawings, preferably so as to form a sub-surface or foundation which is high in the center and gradually inclines toward each side to form a proper water 85 shed.

As previously stated in the objects of the invention, it is desirable to move the drag structure laterally at certain times and to facilitate the accomplishing thereof, the jack 95 structure 40 is provided. This jack structure 40 includes the post 41 having the base 42 upon its lower end, which is provided for engagement with the sub-grade surface when the jack structure is in use. This post 41 100 has a head 43 upon its upper end, comprising a pair of spaced arms extending upon opposite sides of the post, as clearly shown in Figure 8 of the drawings, from one arm to the other of each pair of which extends a 105 rivet or pin 44 which is engaged by the dog structure 45 during the use of the jack in either raising or lowering the jack structure. The dogs 45 are connected to the operating levers 46 and 47, one being connected to each 110 lever, and these levers are pivotally connected to the dog 45 intermediate their ends having their lower inner ends slotted as shown at 48, and connected to the post 41 for operating the jack structure. The levers 46 and 115 47 are pivotally carried by the truck structure 50 comprising spaced axles 51 and 52 connected by connecting bars 53 to which the levers 46 and 47 are pivotally connected from 120 which position the levers extend laterally of the frame structure 32. However, if it is desired that the levers 46 and 47 extend longitudinally of the frame 32 they may be mounted upon the axles 51 and 52. Flange rollers 54 are mounted upon the ends 125 of the axles 51 and 52 and engage on a trackway 55 formed on the frame 32, so that when the jack structure 41 is lowered as

- shown in Figure 2 of the drawings, the entire drag structure may be easily swung laterally, upon the jack as a pivot, or since the head structure 43 is rotatably mounted upon the post 41, the entire drag structure may be turned around or rotated upon the jack structure 40 as a pivot for reversing the direction in which the drag structure faces.
- 10 Conveyors 60 and 61 are provided, one travelling in each direction from the center of the drag structure, intermediate the ends thereof, which conveyors are provided for carrying surplus dirt to the sides of the highway or road bed. Each of the conveyor structures comprises a shaft 62 rotatably supported by suitable bearings 63 upon which is mounted a suitable sprocket about which the chains 64 of the conveyor pass.
- 15 The chain 64 has buckets or flights 65 attached thereto at spaced intervals, and these buckets face during the upper run of the chain toward the outer sides or edges of the drag structure, while on the downward run they face toward the center of the drag structure so that they will scoop up the surplus soil and carry it to the side of the drag. The outer end of the chain 64 of each of the conveyor structures travels about a sprocket 66 which is mounted upon a shaft 67. The shaft 67 has a worm 68 thereon, which meshes with the worm gear 69. The worm gear 69 is mounted upon a suitable supporting shaft 70 carried by a supporting frame or bracket structure 71. The worm 69 in turn meshes with a worm gear 72 which projects a slight distance below the lower edge of the side rail 16 or 17 of the frame 15, so that during the travel of the drag over the forms or header boards indicated at A in Figure 2 of the drawings, the worms 72 will be rotated for transmitting motion to the operating shaft 67 of its respective conveyor, to operate the said conveyor for carrying surplus soil to the sides of the roadway.
- 20 Summing up, generically the operation of the improved subgrade drag is as follows: The tool carrying frame 26 is first adjusted at the proper or desired elevation to regulate the depth of the surface of the foundation or sub-grade, below the finished surface of the highway, and the drag structure is then drawn over the header or form boards A by suitable type of propelling means during which movement the harrow teeth 29 will break up the soil at the high places, loosening it, after which it will be engaged respectively by the blades 32^a, 35 and 36, thus levelled to provide the proper shape to the foundation. However, by particular reference to Figures 3 and 4 of the drawings, it will be noted that the cutting edges of the surfacing or cutting blades 35 and 36 projects below the lower edges of the harrow teeth 29, and thus a hard surface for the
- 25 foundation will be formed in the majority of places, the said blades pushing the surplus soil off the top of the foundation or sub-grade. Any surplus soil which is not used in filling up the low places will be conveyed to the sides of the highway or road bed by the conveyors 60 and 61 after the drag structure is filled, the said conveyor structures being positioned to permit the retaining of a certain amount of soil in the drag structure for filling in the low places during the operation thereof.
- 30 When it is desired to move the drag structure laterally the jack structure 40 is operated, in a manner heretofore specified for raising the drag structure off the forms A and permitting it to be swung laterally and through the medium of the rollers 54 and track structure 55 rolled off of one of the tracks A thus partly removing it from the roadway and providing sufficient passage-way for a roller or the like.
- 35 Changes in details may be made without departing from the spirit of this invention, but;
- 40 I claim:
1. In a highway drag or surfacer, the combination of a plurality of flat surfacing blades shaped to fit transversely a road section each having its cutting edge positioned slightly lower than the cutting edge of the next forward blade.
- 45 2. In a highway surfacer, the combination of a supporting frame, a jack structure associated with said supporting frame adapted to elevate said frame for lateral swinging, and means permitting relative movement of said frame away from said jack structure when said frame is elevated.
- 50 3. In a highway surfacer, the combination of a supporting frame, a jack structure associated with said supporting frame adapted to elevate said frame for lateral swinging, and an auxiliary truck structure connected to said jack structure permitting relative movement between said jack and supporting frame.
- 55 4. A grader comprising a frame, a scraping blade carried by said frame, and an endless belt rotatably disposed forwardly of said blade and operating in a plane transversely of the plane of said frame, said endless belt having earth engaging members thereon which are disposed upwardly of the scraping edge of said blade and adapted to operate upon the earth gathered forwardly of said blade.
- 60 5. In a highway drag or surfacer, the combination of a supporting frame, a tool carrying frame carried thereby, a plurality of surfacing blades carried by said tool carrying frame and each having its cutting edge positioned slightly lower than the cutting edge of the next forward blade, and a jack structure associated with said tool

carrying frame whereby the drag or surfa-
cer structure may be elevated out of oper-
ative position.

6. In a highway drag or surfacer, the
5 combination of a supporting frame, a tool carry-
ing frame carried thereby, a plurality of
surfacing blades carried by said tool carry-
ing frame and each having its cutting edge
positioned slightly lower than the cutting
10 edge of the next forward blade, a jack struc-
ture associated with said tool carrying frame
whereby the drag or surfacer structure may
be elevated out of operative position, a track
structure carried by said tool carrying
15 frame, and a truck structure carried by said
jack structure and engaging said track struc-
ture to facilitate lateral movement of the
drag or surfacer.

7. In a highway drag or surfacer, the
20 combination of a supporting frame, a plu-
rality of surfacing blades carried thereby, a
track structure carried by the supporting
frame, a jack structure, a truck structure
carried by said jack structure and engag-
25 ing said track structure, said jack structure
adapted to be operated to elevate the sup-
porting structure out of an operative posi-
tion.

8. In a highway drag or surfacer, the
30 combination of a supporting frame, a plurality
of surfacing blades carried thereby, a track
structure carried by the supporting frame,
a jack structure, a track structure carried by
said jack structure and engaging said track
35 structure, said jack structure adapted to be
operated to elevate the supporting structure
out of an operative position, and a conveyor
structure carried by said supporting frame.

9. In a highway drag or surfacer, the
40 combination of a supporting frame, a plu-
rality of surfacing blades carried thereby,
a track structure carried by the supporting
frame, a jack structure, a track structure
carried by said jack structure and engag-
45 ing said track structure, said jack structure
adapted to be operated to elevate the sup-
porting structure out of an operative posi-
tion, a conveyor structure carried by said
supporting frame, and means operable by
50 the travel of the drag structure for operat-
ing said conveyor structure.

10. In a highway surfacer, the combina-
55 tion of a trackway, a supporting frame slid-
ably mounted on said trackway, a tool car-
rying frame, road scraping tools carried
thereon, means permitting adjustment of
said tool carrying frame with respect to said
supporting frame, a jack structure carried
by said tool carrying frame and movable
60 longitudinally thereon, said jack structure
provided to elevate the entire surfacer for
removing it from the highway.

11. In a highway surfacer, the combina-
65 tion of a trackway, a supporting frame slid-
ably mounted on said trackway, a tool car-

rying frame, road scraping tools carried
thereon, means permitting adjustment of
said tool carrying frame with respect to said
supporting frame, a jack structure carried
by said tool carrying frame and movable
70 longitudinally thereon, said jack structure
provided to elevate the entire surfacer for
removing it from the highway, first swing-
ing the same upon the jack as a pivot and
then moving the entire surfacer laterally
75 off of the track way.

12. In a highway drag or surfacer, the
combination of a supporting frame, a plu-
rality of surfacing blades each having its
80 cutting edge positioned slightly lower than
the cutting edge of the next forward blade,
means carried by the supporting frame for
elevating the drag or surfacer structure out
of an operative position, and a conveyor
85 structure carried by said drag structure, for
conveying soil laterally of the drag struc-
ture.

13. In a highway drag or surfacer, the
combination of a supporting frame, a con-
veyor structure carried thereby, an operat-
ing shaft for said conveyor structure, a
90 gear carried by the supporting frame and
projecting below the lower edge thereof for
frictional contact with the roadway for ro-
tation during the travel of the drag struc-
ture, and means operatively connecting said
95 gear and conveyor operating shaft.

14. In a highway drag or surfacer, the
combination of a supporting frame, a con-
veyor structure carried thereby, and in-
100 cluding an operating shaft, a worm upon
said operating shaft, a worm gear carried
by the supporting frame and meshing with
said worm, a second worm gear carried by
said supporting frame and projecting be-
105 low the lower edge thereof for rotation dur-
ing travel of the drag or surfacer, said
worm gears meshing whereby said operat-
ing shaft will be rotated during travel of
the drag structure for operating said con-
veyor.

15. In combination with a vehicle carried
scraping blade, adapted to be adjusted in
elevation to engage and scrape the surface
of a road, of an endless belt having a lower
115 side movably disposed longitudinally along
the front side of said blade, said belt having
earth engaging members adapted to break
lumps of earth gathered in front of said
blade, and means for driving said belt to
break said earth.

16. A grader, comprising in combination
a frame, a scraping element mounted on
said frame, a pair of conveyors mounted
forwardly of said scraping element, and
125 longitudinally thereof, and means for driv-
ing said conveyors in opposite directions to
gather material collected by said scraper,
and to deposit the same laterally of said
grader.

17. A grader, comprising in combination
a frame, a scraping element mounted on said
frame, a pair of conveyors mounted for-
wardly of said scraping element and longi-
tudinally thereof, each of said conveyors
operating for substantially one-half of the
length of said scraping element, and means
for driving said conveyors in opposite direc-
tions upon movement of said grader, to col-
lect material from forwardly of said scrap-
ing element, and to deposit the same later-
ally of said grader. 10

CHARLES M. BUTTS.
